MOSES CULBERTSON, OF KELFIELD, SASKATCHEWAN, CANADA.

TRAIN STOP-SIGNAL.

1,383,908.

Specification of Letters Patent.

Patented July 5, 1921.

Application filed October 29, 1920. Serial No. 420,451.

To all whom it may concern:

Be it known that I, MOSES CULBERTSON, a subject of the King of Great Britain, residing at Kelfield, in the Province of Saskatchewan and Dominion of Canada, have invented certain new and useful Improvements in Train Stop-Signals; and I do hereby declare the following to be a full, clear, and exact description of the invention, such as 10 will enable others skilled in the art to which it appertains to make and use the same.

The object of the invention is to provide simple and relatively inexpensive means for signaling the engineers and other members 15 of the crews of trains approaching each other within danger distances on the same track to guard against head on collisions by giving the engineers or crews of said trains ample warning to bring their respective 20 trains to a stop, and thus avoid the property damage and loss of life incident to collisions which occur by reason of incorrect or misunderstood train orders, or the disregard of signals in railway traffic, and with these objects in view the invention consists in a construction and combination of parts of which a preferred embodiment is shown in the accompanying drawing, wherein—

Figure 1 is a side view of the apparatus 30 as shown in operative position carried by opposing engines on the same track.

Fig. 2 is a detail side view partly in section of the front end of the apparatus; and

Fig. 3 is a similar view of the rear or locomotive end of the same.

The apparatus consists essentially of a tube or barrel 10 extended forward from the locomotive 11 on the line of the track 12 in advance of the locomotive and supported by 40 suitable trucks 13 preferably of light construction but of a weight sufficient to maintain the same upon the track rails, the front end of the barrel being provided with an explosion chamber 14 for the reception of a cartridge 15. The discharge of said cartridge is effected by a firing pin 16 which is carried by a head 16^a adapted for contact with the opposing head of the train approaching from the opposite direction and 50 provided with a similar equipment as indicated in Fig. 1.

The barrel 10 is made in sections which are united by couplings 10^a, and it is supported upon the trucks 13 by rods 13^a. The 55 rods are connected to the trucks 13 as at 13^b and to the couplings 10^a as at 13^c. The head

16^a is supported by a rod 16^b which is secured to the front truck by a bracket 16^c.

At the rear end of the barrel is a tapered nozzle 17 arranged in a funnel 18 for directing the projectile 15^a against the firing pin 19 employed for exploding a blank cartridge 19^a. To insure the actuation of the firing pin 19 by the projectile 15^a, the former is provided with a plurality of prongs 19^b 65 upon which the projectile impinges when it passes into the funnel 19. The cartridge 19^a is mounted in the chamber 20 of an engine barrel 21 the muzzle 22 of which is disposed under a suitable downwardly deflected shield 70 23. The charge of the cartridge 19^a in the engine barrel is designed to make a sound sufficient to attract the attention of the engineer and if necessary other members of the train crew so as to warn the engineer and such members of the train crew to take the proper precautions in the way of cutting off the steam and applying the brakes, to guard against the contact of the locomotives and insure the stopping of the train before a collision can occur. 75

Obviously the forwardly projecting apparatus will be more or less damaged or mutilated by the contact thereof after the signal has been given and before the trains can be 85 brought to a stop, but the cost of such apparatus is negligible as compared with that of the locomotives and train equipment, and hence may readily be sacrificed in order to save the loss of the train equipment as well 90 as to minimize the loss of life incident to the destructive contact of the locomotive.

The forwardly extending barrel of the apparatus will follow the curvature of the tracks, the same being of sufficient flexibility 95 for this purpose, so that the device will serve its purpose upon curves as well as upon straight lines of tracks, the funnel 18 serves to permit of a certain angular movement of the nozzle 17 without disturbing the 100 relations of the parts sufficiently to involve the failure of the projectile traversing the barrel 10 to engage and properly actuate the firing pin of the engine barrel.

Having thus described the invention, what 105 I claim is:

1. A safety signaling apparatus for trains having a forwardly extending truck supported barrel adapted for projecting in advance of a locomotive and provided at its 110 forward end with explosive means for discharging a projectile rearwardly through

said barrel, and a detonating apparatus carried by the locomotive for actuation by a projectile traversing the barrel.

2. A safety signaling apparatus for locomotives having a truck supported barrel extending in advance of a locomotive to traverse the track rails and provided at its forward end with a means for discharging a projectile rearwardly through the barrel upon contact of the forward end of the same with an obstruction, an engine barrel carried by the locomotive and having detonating means including a firing pin disposed in the path of a projectile traversing said first named barrel, the forward end of the engine barrel being provided with a funnel for receiving a nozzle at the rear end of the first named barrel.

3. A safety signaling apparatus for locomotives having a truck supported barrel extending in advance of a locomotive to traverse the track rails and provided at its forward end with a means for discharging a projectile rearwardly through the barrel upon contact of the forward end of the same with an obstruction, an engine barrel carried by the locomotive and having detonating means including a firing pin disposed in the path of a projectile traversing said first named barrel, the forward end of the engine

barrel being provided with a funnel for receiving a nozzle at the rear end of the first named barrel, and a downwardly deflecting shield covering the muzzle end of the engine barrel.

4. A safety signaling apparatus for trains comprising trucks, a sectional barrel supported upon the trucks having a front cartridge receiving chamber, a firing pin, a rod secured to the front truck, and a bumper head carried by said rod and having the firing pin connected thereto.

5. A safety signaling apparatus for trains including trucks, a sectional barrel supported upon the trucks and provided at its forward end with explosive means for discharging a projectile rearwardly through the barrel.

6. A safety signaling apparatus for trains including a barrel carried by the train and having a cartridge receiving chamber, a firing pin in said chamber, and means in advance of said barrel for discharging a projectile against said firing pin.

In testimony whereof I affix my signature in presence of two witnesses.

MOSES CULBERTSON.
